FIG. 2

FIG. 3

Des. 235,111

PAGE 3

FIG. 4

FIG. 5

FIG. 6

FIG. 1 is a top perspective view of a small animal playground showing our new design.

FIG. 2 is a rear elevational view thereof;

FIG. 3 is a left side elevational view;

FIG. 4 is a front elevational view of an alternate arrangement of the small animal playground;

FIG. 5 is a right side elevational view thereof; and

FIG. 6 is an enlarged scale top plan view thereof.

The bottom of the small animal playground is plain and unornamented.

We claim:

The ornamental design for a small animal playground, as shown and described.
